WINDSHIELD-VISOR-CLAMP
COMBINATION

John Wardan, Hartford, Conn.

Application September 17, 1941, Serial No. 411,171

8 Claims. (Cl. 296—97)

My invention relates to improvements in windshield-visor-clamp combinations involving a visor made of flexible material, such as Cellophane that is translucent and colored to reduce glare-effect, such as yellow or green, that is operatively housed within a suitable casing so as to be withdrawable therefrom and located within the zone of vision of the operator of an automobile in opposition to the inner face of the glass of the windshield, clamp means being provided for removably mounting the housing on a frame or sash member and the object of my improvement is to produce a windshield-viso-combination that permits of removable application thereof to the windshield structure by reason of the clamping means, which means may be modified in detail for the purpose of effecting different results.

In the accompanying drawings:

Figure 1 is a diagrammatic rear elevation of my improved windshield-viso-clamp combination showing the visor structure supported from the left windshield sash member.

Fig. 2 is a similar view of a double structure, with a clamp mounted in the middle frame or sash member and visors on either side of the middle clamping screw and operative respectively to the right and left.

Fig. 3 is a sectional view on the line 3—3 of Fig. 1 showing the clamping structure and associated parts drawn to scale.

Fig. 4 is a similar view of the double structure on the line 4—4 of Fig. 2.

Fig. 5 is a face view of the single-housing supporting plate of Fig. 1.

Fig. 6 is a similar view of the double-housing supporting plate of Fig. 2.

Fig. 7 is a tilted-face view of a frame or sash engaging member, showing the integral loop with the perforation for the clamping screw.

Fig. 8 is a similar view of the locking member with its loop and clamping fingers and wings.

Fig. 9 is a similar view of one form of the clamping plate element of the clamping means.

Fig. 10 is a similar view of the visor end structure.

Fig. 11 is a view of the clamping screw.

Fig. 12 shows a clip with integral hook as one form of the restraining structure.

My improved windshield-viso-clamp combination comprises a visor 10 of Cellophane or the like that is translucent and colored suitably to reduce glare, green or yellow, that under conditions of use is positioned along the inner face of the glass 11 of the windshield 12. In the form that is shown in Fig. 1 the visor is supported from

the left sash member 13; is housed within a roll housing 14 from which it emerges through a slot 15; operating in opposition to a spring within the housing; the free end being tipped by a metal strip 16; and by means of an opening 17 is anchored on a hook 18 or pin or other suitable projection. The hook 18 is supported by means of a screw 19 and associated parts mounted on a middle sash member 20.

10 The roll housing 14 is rigidly secured to a plate 21 that is part of clamping means that provide for removable connection with the sash member. At the middle sash member there is a generally similar plate 22 below the hook and that is part 15 of a clamp combination that serves as the securing means for the hook and that differs from the plate 21 only in that there is nothing mounted thereon. Another modification of the plate structure is the plate 23 on the middle sash member 24 20 of the arrangement shown in Fig. 2 and that provides support for two rolls respectively 25 at the right of the middle and 26 at the left from which emerge the visors 10, the one directed towards the right sash member and the other to the left sash member 13. On the right sash member 26 is mounted a hook 27 that is integral with another plate modification 28. On the left sash member 13 is a plate form 29 that has the hook 30 integrally incorporated and directed inwardly 30 toward the right in distinction from the hook 27 that is directed toward the left.

All forms of the different plates described are made of sheet metal; have exposed and accessible face spaces that are available for support of one or more rolls or the like and each is an active element of one of the forms of clamp structure. To this end an opening 31 is provided of rectangular form the right and left border walls 32 of which constitute the detailed elements.

40 Considering plate 21, a loop 33 of sheet metal is entered through the opening 31; the loop arms 34 scraping along the border walls 32; preventing spread thereof; and bringing them closer together in case they are already spread apart; the loop bridge 35 being perforated for admitting the clamping screw 36; a nut 37 being provided.

A locking member 38 is provided, of sheet metal; generally in the form of a loop that caps the loop 33; having a perforated bridge 39 that is 50 spaced from the bridge 35 by a gap 40 that provides working space; dependent from the bridge 39 are the side arms 41 located alongside the loop arms 34; the ends 42 of said arms press against the opposed supporting and binding plate 21. Thus means are provided for effecting a

clamping pressure on the plate element by means of the clamping screw. Extensions 43 may be provided outwardly from the edges or ends 42 of the locking loop, thus extending the surface contact.

The support for the inner clamped loop 33 is some means for engaging the supporting sash member and will vary in detail to conform with various sash structures. In all cases the plate element presses against wing-like projections 44 from the ends of the loop arms; on each side dependent from the wing ends are short arms or fingers 45 that are spaced apart approximately the width of the sash member.

At the free ends of the fingers 45 are important acting elements in the form of inwardly directed claws 46 forming with the fingers hook-like gripping structures.

Said claws 46 engage back of the free edges 47 of the sash structure. Said sash structure or member 13 may be plain and flat having an exposed main face 48 that is substantially in parallelism with the glass, as shown, or may be shaped and projected rearwardly and outwardly from the face of the glass. The details of the gripping part will be formed to correspond. Invariably it is believed that the exposed main face will be bordered by or merge with side faces 49 and these latter will be provided with the free edges 47 mentioned that are available for gripping.

The multiple-plate clamping combination, providing the intermediate element with the exposed face for receiving the device shown and described in the form of the roll housing can be usefully employed for the support of other forms of useful devices, such as for instance, an ash receiver or the like.

I claim as my invention:

1. A clamp structure for securing a visor or the like to a windshield structure comprising a three plate arrangement with a screw and nut for effecting the clamping, said plates being defined generally as bottom, intermediary and top, said intermediary plate serving as the support for the visor or the like, said bottom plate having laterally spaced claw structures for a windshield supporting structure or the like, an integral loop on the bottom plate threaded through an opening in the intermediate plate and superimposed by a loop on the top plate, the latter pressing against the intermediate plate by means of feet provided by the side-loop members of the top plate loop, all held together and secured to the windshield part.

2. A clamp made up of three sheet metal members, each of which is of itself a substantially symmetrical structure, respectively, a bottom member, an intermediate member, and a top member, said bottom member having at the middle a loop that is perforated for a clamping screw at the middle of the loop bridge, side arms depending from the bridge that merge by their ends into outwardly projecting wings, the ends of the wings merging with dependent claw members that have inwardly directed gripping edges, all adapted to be deflected outwardly for being projected into engaging position with a support such as a windshield supporting or frame member and to be closed against the same for holding, said intermediate member having an opening in a substantially plain flat structure the border walls of which opening are adapted to bear against the said side arms for effecting a closing of the bottom member to the holding position, the general

face of the intermediate member being exposed and available for the support of a visor holding element or the like, said top member comprising a sheet metal structure having at the middle a loop that is adapted virtually to ride upon the loop of the bottom member, with a bridge at the middle that is also perforated for the screw and is in slightly spaced relation to the enclosed bridge, having side arms dependent from the bridge that extend downwardly into bearing engagement with the interposed intermediate member by the arm ends, integral outwardly directed wings extending the bearing contact, a clamping screw and nut serving to effect the clamping pressure.

3. In a windshield-visord-clamp combination, a sash member at one side of the windshield proper that has a periphery that comprises a rear face, side faces projected forwardly from the edges of said rear face and a front face that comprises in laterally opposed relation the edge portions of said side faces, and a clamp structure that generally encloses said periphery, composed of a plurality of sheet metal members that are adapted to make supporting engagement with said sash member by screw and nut means, claw-like elements integral with one of said sheet metal members in opposed clamping engagement with said edge portions of the side faces operating as the clamp-holding means, another of said sheet metal members having an exposed and accessible face for mounting thereon a housing for a visor whereby laterally spaced edge portions of the sash member in cooperation with screw-thread means operate to provide positively operating means of support for the visor.

4. In a windshield-visord-clamp combination as described in claim 3, a second sash member spaced laterally from the first mentioned sash member, a second clamp structure in clamping engagement with said second sash member and comprising a sheet metal member that has an exposed and accessible face on which is mounted a hook-like element for securing the free end of a visor projecting from said housing.

5. In a windshield-visord-clamp combination, a sash member of a windshield structure located to one side of the windshield proper that has laterally spaced free and accessible edges, a clamp structure having screw-thread clamping means having claw-like elements for being opposed to said edges and effecting supporting engagement therewith responsive to operation of said screw-thread means, a plate serving as one of the elements of said clamping structure and having a relatively free face portion, and a housing for a visor mounted on said free face portion whereby free and accessible edges of the sash member in cooperation with screw-thread means operate to provide positively operating means of support for the visor.

6. In a windshield-visord-clamp combination, a sash member of a windshield, a clamp adapted to make supporting clamping engagement therewith and comprising a plate as one of its elements, said plate being provided with an opening and a relatively free and accessible face portion bordering said opening, border edges of said opening cooperating with another element of said clamp in effecting clamping with said sash member, and a housing for a visor mounted on said face portion whereby said plate does double duty respectively as a clamping element and a support.

7. In a windshield-visord-clamp combination, a windshield sash member having a rear face re-

mote from the glass and a pair of spaced seats at the front opposed to the glass, a clamp constructed and arranged to grasp said member by being opposed generally to said rear face and having spaced seat structures for cooperating with said spaced seats, being composed of a set of cooperating sheet metal parts with screw thread means for effecting the clamping, and being provided with a relatively open face, a housing for a windshield visor being mounted on said open face.

8. In a windshield-viso-clamp combination as

described in claim 7, a second sash member spaced from the first sash member, a second clamp for grasping said second sash member and also being provided with an open face, a visor generally housed in said housing having retractile means tending to withdraw the visor within the housing, a free end of the visor provided with a puncture or the like for receiving a hook or the like, and said hook being supported from said second open face.

JOHN WARDAN.
